CLAIM

I claim the ornamental design for a vehicle wheel, as shown and described.

DESCRIPTION

FIG. 1 is a perspective view of the vehicle wheel showing my new design;

FIG. 2 is a front view of the vehicle wheel; and,

FIG. 3 is a cross-sectional view taken along the line 3-3 of FIG. 2.

The broken lines in the drawings depict portions of the vehicle wheel that form no part of the claimed design.
